UNITED STATES PATENT OFFICE.

MIKE LUTENBERGER, OF BLOCTON, ALABAMA.

CAN OPENER.

Application filed July 12, 1923. Serial No. 651,056.

To all whom it may concern:

Be it known that I, MIKE LUTENBERGER, a citizen of Hungary, residing at Blocton, in the county of Bibb and State of Alabama, have invented certain new and useful improvements in Can Openers, of which the following is a specification.

This invention relates to new and useful improvements in can openers.

10 An important object of the invention is to provide a can opener which may be quickly and easily adapted for accommodating cans of different sizes.

15 A further object of the invention is to provide an opener of the above mentioned type which is capable of completely cutting a portion from the end of a can with a single movement of the cutting element.

20 A still further object of the invention is to provide a can opener of simple construction, strong, and durable, and one that may be manufactured at a nominal cost.

25 Other objects and advantages of the invention will be apparent during the course of the following description.

30 In the accompanying drawing forming a part of this specification and in which like numerals are employed to designate like parts throughout the same,

35 Figure 1 is a side elevational view of a can opener embodying this invention,

Figure 2 is a top plan view of the opener shown in Fig. 1,

40 Figure 3 is a vertical sectional view, partly in elevation, taken on line III—III of Fig. 1,

Figure 4 is a fragmentary side elevational view showing a modified form of securing means for the cutting element, and

45 Figure 5 is a vertical sectional view taken on lines V—V of Fig. 4.

50 In the drawing, wherein for the purpose of illustration is shown the preferred embodiments of this invention, the numeral 5 designates a substantially rectangularly-shaped base plate which is provided at one end with an angularly arranged substantially L-shaped extension 6 that is provided in its foot portion 7 with a threaded aperture 8 that is adapted for operatively receiving the clamping screw 9, as best shown in Fig. 1. The opposite end of the base plate 5 is provided with an offset lug 10 that is adapted for operatively carrying the ten-

sion screw 11, as shown. It will be seen 55 that the clamping screw 9 and tension screw 11 may be employed for removably securing the base plate 5 to a suitable support 12 which may be in the form of a table or shelf. The base plate 5 is further provided at its 60 four corners with apertures 13 through which suitable securing means, such as bolts or screws, may be passed when it is desired to permanently secure the base plate to a 65 supporting object.

Rotatably secured to the base plate 5, as by the rivet or screw 14, is a block 15 which is integrally formed with a substantially rectangularly-shaped perpendicular post 16 having a longitudinally extending elongated slot 17 formed therein. The opposite longitudinal edges of this post 16 are provided with saw teeth formations 18 and 19 with the teeth 18 arranged in staggered relation to the teeth 19. The block 15 and post 16 70 are rotatably secured to the base plate 5 by means of a counter sunk rivet or screw 14 so that the parts supported by said post may be swung horizontally about the vertical axis of said rivet 14 and the opener be thereby brought, as will be hereinafter explained, centrally over the can to be opened. Moreover this arrangement permits either of the 75 series ratchet teeth 18 or 19 to be used at will reversing the position of this part.

80 A handle member 20 is provided with a bifurcated end portion 21 having a longitudinally extending slot 22 formed in each side section of the said bifurcated end, as best shown in Figs. 1 and 2. For the purpose of adjustably securing this handle 20 to the upright rectangularly-shaped post 16, there are provided headed bolts 23 and 24 that are inserted through transverse openings formed in the side sections of the bifurcated end 21 and are secured thereto by means of the thumb nuts 25 and 26 respectively. It will be noted that the transversely extending bolts 23 and 24 are spaced different distances from the end face of the bifurcated end 21 of the handle member 20 and that they are spaced from each other a greater distance than the distance between the side walls of the slot 17 and the outer edges of the saw teeth 18 and 19. The headed bolt 23 is adapted for slidably occupying the longitudinally extending elongated slot 17 formed in the said post 16 while the 85 90 95 100 105

headed bolt 24 is adapted for selectively engaging the teeth formed in the longitudinal edges of the said post.

Slidably positioned between the side sections of the bifurcated end 21 is a substantially rectangularly-shaped shank 27 that is formed integrally with an inverted cup-shaped cutting element 28 having diametrically positioned outwardly extending lugs 29 formed thereon. The lower edge of this cutting element 28 is provided with alternately arranged large and small cutting edges 31 which may be of any suitable formation. For the purpose of adjustably securing this cutting element 28 to the handle 20, a headed bolt 32 has been provided and is inserted through a suitable transverse opening formed in the said lug 27 and also slidably engages the elongated slot 22 formed in the opposite side portions of the bifurcated end 21. A thumb nut 33 is provided for securing the said cutting element in its desired adjusted position.

In Figs. 4 and 5 there is shown a modification which embodies the means for securing the cutting element to the bifurcated end 21 of the handle 20. As has just been suggested the form of handle 20 and bifurcated 21 disclosed and described in reference to Figs. 1 to 3 inclusive is identical in this modified form of the invention. The cutting element 28 with the lugs 29 and cutting edges 30 and 31 are also similar. The modification, therefore, consists of forming the shank 27^a with an externally threaded reduced extension 27^b upon which is operatively mounted the thumb nut 33^a. It will be seen that with the shank 27^a positioned between the side portions of the bifurcated end 21, the thumb nut 33^a will tightly clamp the said bifurcated end 20 against the upper flat surface of the cutting element 28 for the purpose of securing the latter in its desired adjusted position.

The operation of the device is as follows:—

When a can, as designated by the character C, is placed upon the base plate 5 in vertical alinement with the cutting element 28 the said bifurcated end 21 is raised or lowered upon the upright post 16 for the purpose of bringing the cutting element 28 in proper position in respect to the upper end of the said can and for placing the handle member on substantially a horizontal plane. Due to the fact that the headed bolts 23 and 24 are spaced apart a greater distance than the distance between the walls of the elongated slot 17 and the outer edges of the saw teeth 18, the headed bolt 24 will be allowed to ride upwardly or downwardly past these said edges of the saw teeth. After the cutting edges 30 have been moved into engagement with the top of the can C, pressure applied to the outer

end of the handle 20 will cause the handle to slide upon the bolt 32 for placing the bolt 24 in engagement with the proper tooth formation 18. Further pressure upon the end of the handle 20 will cause the cutting elements 28 to exert a downward pressure against the top of the can C while the bolt 24 will exert an upward pressure against the horizontally extending face of the saw tooth formation against which it is bearing. It will be very apparent that any additional pressure brought to bear against the end of the handle 20 will not cause further movement of the latter until the can top or the saw tooth formation yields to the pressure placed thereupon. The can top, of course, will be the first to yield and the desired result will be accomplished. It will be apparent that the bolt 23 is employed for preventing the handle 24 from accidentally becoming disconnected from the post 16 and, also, for retaining the handle 20 in a proper position in respect to the post 15 for insuring engagement between the bolt 24 and one of the saw teeth 18. The purpose of the swivel connection between the block 15 and the base 5 is to allow the cutting element 28 to be moved on a horizontal plane for the purpose of properly centering the same in respect to the can C. It is to be understood that the cutting element 28 is not to be limited to a circular formation, as is disclosed by the various views, for the same may be formed into a rectangle, a triangle, a straight edge, or any other suitable formation for handling cans that are of substantially similar formation. The saw teeth formations 18 and 19 have been provided in staggered relation upon opposite longitudinal edges of the post 16 for the purpose of allowing a finer vertical adjustment of the cutting element 28. By removing the thumb nut 25 from the bolt 23 and withdrawing the latter, the handle may be removed from the upright post 16 which may then be reversed for placing the saw teeth 19 in the position now occupied by the teeth 18. The handle and cutting element may then be connected to the post 16 in the manner heretofore described.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described the invention, I claim:—

1. In a can opener, a base, a post rotatably mounted on the base and having oppositely disposed sets of ratchet teeth, the teeth of one set being staggered with re-

spect to the teeth of the other set, a handle shiftable to either side of said post, a fulcrum bolt carried by the handle and selectively engageable with the ratchet teeth, and 5 a can opener supported by said handle.

2. In a can opener, a base, a post rotatably mounted on the base and having oppositely disposed sets of ratchet teeth, the teeth of one set being staggered with respect to the 10 teeth of the other set, a handle shiftable to

either side of said post, a fulcrum bolt carried by the handle and selectively engageable with the ratchet teeth, a can opener supported by said handle, means to permit shifting of the can opener along said 15 handle, and means to secure the can opener selectively in shifted position.

In testimony whereof I affix my signature.

MIKE LUTENBERGER.
